Application filed June 8, 1929. Serial No. 31,597. Term of patent 14 years.

To all whom it may concern:

Be it known that I, FRANK J. The drawing is a perspective view showing my new design for a box.

The linings for colors partially shown on the defined areas 1, 2, and 3 indicate that said defined areas are colored in contrast with the colors of the areas 4, 5, 6 and 7, the colors being continued over the several areas.

I claim:

The ornamental design for a box, substantially as shown and described.

FRANK J. SCHLEICHER.
